UNITED STATES PATENT OFFICE.

EUGENE FREY, OF OAKLAND, CALIFORNIA.

AUTOMOBILE-SIGNAL.

1,277,303.

Specification of Letters Patent. Patented Aug. 27, 1918.

Application filed May 23, 1917. Serial No. 170,774.

To all whom it may concern:

Be it known that I, EUGENE FREY, a citizen of the United States, residing at Oakland, in the county of Alameda and State of California, have invented certain new and useful Improvements in Automobile-Signals, of which the following is a specification.

This invention relates to improvements in signaling devices for vehicles adapted to indicate to an approaching vehicle the direction which the one carrying the signal is going to take.

Some of the principal objects of the present invention are to provide a device which is substantial in construction, which is effective in operation, and which will provide a signal both by night and day.

Other objects of the invention are to so construct the signal that it may be easily attached to existing vehicles and will be visible both from the front and rear.

With these and other objects in view, the invention consists of certain novel features of construction, combinations and arrangements of parts hereinafter described and more specifically pointed out in the appended claims; it being understood that changes in form, proportion, size and minor details of construction within the scope of the claims may be resorted to without departing from the spirit of the invention or sacrificing any of the advantages thereof.

Referring to the drawing forming a part of this specification,

Figure 1 is a view in section through a vehicle looking toward the front thereof and showing two of my improved signals in position.

Fig. 2 is a view in elevation of one of the signals in its extended position.

Fig. 3 is a view in elevation taken from the opposite side of Fig. 2 and showing the signal almost folded.

Fig. 4 is a view in plan with the outer end of the signal in its open position.

Referring to corresponding parts of the several views by the same numerals of reference, 1 denotes the vehicle body and 3 and 4 denote two of my improved signals, one of which is mounted on each side of the vehicle.

Each of these signals consists of a bracket 5 which is adapted to be attached to some rigid part of the vehicle body as the windshield frame, instrument-board or similar structure.

Rigidly attached in this bracket is an arm 6, this arm being inclined at substantially

45 degrees, having pivotally mounted on its outer end, a link 7. To the outer end of this link, and to the arm 6, intermediate its ends, are pivotally attached links 8 and 9 respectively, which links are pivotally attached to each other at their centers and have the outer ends 9' connected to other similar links, thus forming a lazy-tongs arrangement of any desired number of sections. The rivets or other fastening means 8' have a central opening for the purpose herein-after set forth.

The outer end links of this lazy-tongs are denoted by 10 and 11. These links are pivotally connected at their center as shown at 12 and on the same pivot-pin is connected a socket member 13.

Denoted in general by 14 is a square box-like structure, the sides 20, 22 and 23 of which are hinged to each other on the four corners. The opposite corners 16 and 17 which are in alinement with the axis of the lazy-tongs, are provided with openings 18 sufficiently large to allow the passage of the socket member 13 and an illuminating lamp 15 which is carried thereby.

The pivot-pin 21 of the hinged corner 17 passes through the socket member 13 whereby the latter is always symmetrically disposed with respect to the lazy-tongs and the box-like member 14.

The outer ends of links 10 and 11 are attached to the sides 22 and 23 by means of springs 24. One end of each of these springs is clamped rigidly to the box sides while their other ends are pivotally attached to the ends of links 10 and 11. This construction provides for the necessary relative movement between the ends of the links and the box sides and at the same time assists in restoring the parts to their normal folded position.

A flexible membrane 25 is attached to the sides of member 14 and is formed in two triangular sections, each of which is creased along the lines 26 whereby, when the box-like structure is collapsed, the membrane will fold as shown in Fig. 3.

From the socket 13 a flexible cable 30 is provided which passes through the openings of the rivets 8' of each alternate link of the lazy-tongs, its other end running to a source of electric current. The other side of the circuit may be grounded on the frame and I provide a switch which causes the lamp to be lighted only when the signal is extended.

Pivotally mounted on the same point with

link 7 is a bell-crank lever 31 having its one arm 32 pivotally attached to the junction of arms 7 and 8 and having connected to its other arm 33, the operating rod 34.

5 On arm 6 is a metallic clip 35 which is insulated therefrom and arranged to make contact with the bell-crank lever 33 when the latter is moved downwardly. The other side of the electrical circuit is connected to 10 this clip as by the conductor 36, which, in turn, leads to the source of current.

The operating means for these signals are preferably mounted on the steering post 37 as shown in Fig. 1 and consists of the lever 15 arms 41 and 42 for signals 3 and 4 respectively. To these arms are fastened the other ends of the operating rods 34, which pass through suitable flexible tubular structures 38 whereby the movement of the lever arms 20 will cause the reciprocation of the rods 34.

The signals are normally retracted as shown at 3 and when the turn is to be made, say to the right, then the right hand lever 42 is moved causing the rod 34 to slide 25 within the tubular support 38 thereby rotating the bell-crank lever 31 of signal 4. This extends the lazy-tongs arrangement and the ends of the outer links of the latter move the box-like member so that its sides 30 open in a square shape as shown in Fig. 2.

A flexible membrane is stretched taut and the lamp assumes a position approximately in the center of the box 23. This membrane is preferably of a red color and when the 35 bell-crank reaches its lowermost position, contact is made with the clip 35 whereby a circuit is established to the metallic structure comprising the lazy-tongs and the lamp is lighted. It will, of course, be understood 40 that during the day suitable means are provided for throwing the electrical circuit out of operation.

Thus in daytime the signal is extended about eighteen inches from the side of the 45 car being thereby clearly visible either to an approaching or a following vehicle and at night, not only is it thus extended, but the membrane is illuminated giving an additional warning to a following vehicle.

50 Having thus described my invention, what I claim as new and wish to cover by Letters Patent, is:

1. A signal of the character described comprising a lazy-tongs having one end 55 fixed, a folding structure carried on the opposite end of said lazy-tongs, a foldable membrane between the sides of said structure and means for extending said lazy-tongs.

60 2. A signal of the character described

comprising a lazy-tongs having its inner end held stationary, a box-like member attached to the outer end of said tongs and adapted to fold or open when said tongs are folded or opened, a flexible membrane extending between the edges of said member, illuminating means back of said membrane, and means for operating said lazy-tongs.

3. A signal of the character described comprising a lazy-tongs having one end 70 fixed, a lever for moving said lazy-tongs, a collapsible rectangular member having two of its sides attached to the outer links of said lazy-tongs, a lamp socket mounted on the outer end of said lazy-tongs so as to be 75 held in alinement with the axis thereof, an illuminating lamp in said socket adapted to be positioned in the center of said rectangular member when the latter is unfolded, and means for completing an electric circuit 80 to said lamp when said lazy-tongs are extended.

4. A signal for vehicles comprising a lazy-tongs having one end adapted to be attached to the vehicle and the other to be extended from the side thereof, a rectangular foldable member carried by the free end of said lazy-tongs, a flexible translucent membrane carried by said member adapted to fold therewith, illuminating means adapted 90 to be positioned back of said membrane when said tongs are extended, and means for completing an electric circuit to said illuminating means when said tongs are extended.

5. A signal for vehicles comprising a series of pairs of links, the links of each pair being pivotally connected to each other at their centers and the ends of each pair being pivotally connected to the end of the adjacent pair, an operating lever pivotally attached to the end of one of the links of the first pair, a fixed arm to which the end of the other link of the first pair is attached, a square foldable member having its sides pivotally attached to each other, spring 105 hinges attaching the end of the outer pair of links to adjacent sides of said square member, a lamp socket attached to the pivotal point of said last pair of links, a pivot pin extending through the hinge of said adjacent sides and said socket, a flexible translucent membrane attached to the sides of said square member, an electric lamp in said socket adapted to be positioned in the center of said square member when the latter 110 is unfolded, and means for completing an electric current to said lamp when said links are moved to unfold said square member.

In testimony whereof I affix my signature.

EUGENE FREY.
